Primary Examiner — Nathan M Johnston(57) **CLAIM**

The ornamental design for gun rack, as shown and described.

DESCRIPTION

FIG. 1 is a front view of one embodiment of gun rack showing my new design, the back view therefore being identical;

FIG. 2 is a right side view thereof, the left side view therefore being identical;

FIG. 3 is a top plan view thereof;

FIG. 4 is a bottom view thereof;

FIG. 5 is an isometric view thereof;

FIG. 6 is a front view of another embodiment of gun rack, the back view therefore being identical;

FIG. 7 is a right side view thereof, the left side view therefore being identical;

FIG. 8 is a top plan view thereof;

FIG. 9 is a bottom view thereof;

FIG. 10 is an isometric view thereof;

FIG. 11 is a front view of another embodiment of gun rack, the back view therefore being identical;

FIG. 12 is a right side view thereof, the left side view therefore being identical;

FIG. 13 is a top plan view thereof;

FIG. 14 is a bottom view thereof; and,

FIG. 15 is an isometric view thereof.
